AUTOMATIC WINDING DEVICE FOR TIMEPIECES

Filed Nov. 9, 1931

UNITED STATES PATENT OFFICE

FRITZ BARBEZAT, OF LA CHAUX DE FONDS, SWITZERLAND, ASSIGNOR TO THE FIRM
MADER & CO., OF CHÉZARD, NEUCHATEL, SWITZERLAND

AUTOMATIC WINDING DEVICE FOR TIMEPIECES

Application filed November 9, 1931, Serial No. 573,980, and in Switzerland September 23, 1931.

This invention relates to automatic winding devices for driving springs of time-pieces, particularly wrist watches and has as its object the provision of a mechanism 5 by means of which the spring of a wrist watch is wound up by the movements of the arm of the watch bearer.

The invention consists in the provision of a supporting member fixed to the wrist strap 10 of the watch and to which the watch case is connected by means of pivoted links permitting the watch case to effect an alternating movement relative to the supporting member, an actuating mechanism being provided 15 between the supporting member and the driving spring to effect winding of the spring owing to the influence of the said relative movement.

In the drawing,

20 Figure 1 is a plan view of a wrist watch in accordance with the invention.

Figure 2 is a side elevation of the watch.

Figure 3 is a section showing the watch movement from the side of the bridges.

25 Figure 4 is a section along the line IV—IV of Figure 3.

In the represented example, the movement 1 is located in the watch case 2 of rectangular shape, mounted on a cradle-like supporting member 3 destined to rest on the wrist of the bearer of the watch. The connection between the watch case and the supporting member is made by means of two pairs of links 4 and 5 adapted to pivot in vertical 30 planes parallel to the longitudinal sides of the watch case.

The two ends of the supporting member 3 are bent up and to each end is secured one end of the wrist strap 6. The links 4 of 40 the first pair are each connected on the one hand to an axis 7 fixed to the cradle 3, and on the other hand by means of pins 8 to the longitudinal sides of the case 2. The links 5 of the second pair have each one end pivoted on an axis 9 of the cradle 3, and their

ends 10 are rigidly connected to a shaft 11, penetrating the case 2 and the movement 1 in which it is rotatably mounted. The shaft 11 is provided with a crank 12 adapted to rotate in an empty space 1' provided in the 50 movement. To this crank is hinged one end 13 of a spring pawl 14 having its other end 15 cooperating with the toothed 16 of a ratchet wheel 17 mounted on a pinion carried by the spring drum shaft. A retaining pawl 18 cooperates with the ratchet 17, while 19 indicates a spring fixed to the movement 1 and to the spring pawl 14 for the purpose of maintaining the end 15 of the pawl constantly in contact with the ratchet 55 17.

The case 2 enclosing the movement 1, and mounted in the described manner on the supporting member 3 can thus move relative to this member owing to the action of 60 shocks produced by the movements of the arm of the watch bearer. The case is guided in its movements by the two pairs of rods 4 and 5 and can thus reciprocate between the limits of its two extreme positions shown in 65 70 full and dotted lines in Fig. 2.

When the watch moves from the left to the right in Fig. 2, the shaft 11 turns slightly in the direction of the arrow f, about the axis 9 into the position shown in dotted 75 lines in Fig. 2, whereby the spring pawl 14 is moved from the right to the left in Fig. 3 relative to the watch and drives the ratchet wheel 17, to wind the main spring. When the watch moves in opposite direction, the shaft 11 also turns in opposite direction to the arrow f and the spring pawl moves from the left towards the right sliding over the teeth of the ratchet which is retained in its position by the pawl 18. The 80 two ends 20 of the strap 6 are secured in such a manner to the supporting member 3 as to penetrate into the cradle and to act as shock absorbers for the movements of 85 the watch and also prevent any noise, the 90

watch coming not in contact with the supporting member.

In order to avoid overwinding of the main spring when this latter is fully wound up, the movement may comprise any known friction connection between the main spring and the drum.

I claim:—

1. An automatic winding device for the driving spring of timepieces, comprising a supporting member for the timepiece, a pair of connecting links pivoted to the timepiece and to the supporting member whereby the timepiece may execute an alternating movement relative to the supporting member, a rotatable operating member carried by the timepiece and connected to the driving spring, a pair of connecting links pivoted to the supporting member and secured to a shaft rotatably mounted in the timepiece, and means for operatively connecting said shaft to said operating member and adapted to rotate said operating member upon relative movement between the timepiece and the supporting member.
2. In a spring driven wrist watch having a watch case including a movement, a cradle-like supporting member for the watch case secured to the wrist strap, connecting links pivoted to the watch case and to the supporting member whereby the watch case may execute an alternating movement relative to the supporting member, a rotatable operating member for the driving spring carried by the watch case, and actuating connections between said operating member and said supporting member to rotate the operating member upon relative movement between the watch case and the supporting member, the ends of the wrist strap penetrating into the interior of the cradle-like supporting member to act as shock absorbers for the movements of the watch case.
3. In a winding device for the driving spring of timepieces, the combination, with a supporting member for the timepiece, of connecting links pivoted to the supporting member and to the timepiece whereby the timepiece may execute an alternating movement relative to the supporting member, a rotatable operating member carried by the timepiece and connected to the driving spring, a crank member rotatably mounted in the timepiece and pivoted to the supporting member, and a pawl carried by the crank member and coacting with said rotatable operating member to turn the operating member upon relative movement between the timepiece and the supporting member.
4. In a timepiece having a spring driven movement, a relatively stationary member, a relatively movable movement carrier capable of effecting an alternating movement relative to the stationary member, a shaft rotatably mounted on the movement and

provided with a crank, said movement including a spring winding ratchet wheel, a pawl mounted on said crank and cooperating with said ratchet wheel, and connecting links secured to said shaft and pivoted to the relatively stationary member, whereby upon an alternating movement between said relatively stationary member and the movement carrier, a movement of rotation is imparted to said shaft to actuate said pawl.

In testimony whereof I affix my signature.

FRITZ BARBEZAT.
